S. J. LEVY

AUTOMOBILE TRUNK RACK

Filed Sept. 9, 1926

Salomon J. Levy.
INVENTOR

UNITED STATES PATENT OFFICE.

SOLOMON J. LEVY, OF SAN FRANCISCO, CALIFORNIA.

DESIGN FOR AN AUTOMOBILE TRUNK RACK.

Application filed September 9, 1926. Serial No. 19,007. Term of patent 7 years.

To all whom it may concern:

Be it known that I, SOLOMON J. LEVY, a citizen of the United States, residing at 510 Bryant St., in the city and county of San Francisco, State of California, have invented a new, original, and ornamental Design for Automobile Trunk Rack, of which the following is a specification, reference

being had to the accompanying drawings, forming part thereof.

The figure is a perspective view of a trunk rack, showing my new design.

I claim.

The ornamental design for an automobile trunk rack as shown.

SOLOMON J. LEVY.
